CLAIM

The ornamental design of a cap, as shown and described.

DESCRIPTION

FIG. 1 is a front view of the cap;

FIG. 2 is a top view of the cap;

FIG. 3 is a bottom view of the cap;

FIG. 4 is a rear view of the cap;

FIG. 5 is a left side view of the cap; and,

FIG. 6 is a right side view of the cap.

The cap is shown partially broken away in the various views to indicate indeterminate length.
